GUN RACK

Filed June 24, 1929

UNITED STATES PATENT OFFICE

WILLIAM J. SPROWLE, OF HUDSON, NEW HAMPSHIRE

GUN RACK

Application filed June 24, 1929. Serial No. 373,210.

This invention relates to racks for securely holding in upright positions articles that are desired for occasional use, and the object of my invention is to provide a rack for holding a series of machine guns all of which may be securely locked in the rack, such racks being especially useful in armories.

With such object in view, my invention consists in the construction and combination 10 of parts substantially as hereinafter described and claimed.

Of the accompanying drawings which illustrate one of the preferred embodiments of the invention:—

15 Figure 1 is a plan view of the rack.

Figure 2 is a side elevation of the same, and
Figure 3 represents a section on line 3—3
of Figure 2.

Similar reference characters indicate similar parts or features in all of the views.

Rigidly supported by a base 12 is a post or standard 13 having annular collars or shoulders 14 which firmly and non-rotatably support three horizontal shelves or disks 15, 16, 25 17, of which the lower one, 15, is the largest and has marginal recesses or notches 18, the upper one, 17, is smaller and has marginal recesses or notches 19, and the intermediate one, 16, is quite small and has arms 20 at the 30 outer ends of which are eyes or sleeves 21 for a circular ring 22 carrying hook members 23. For a reason presently explained, the diameter of the ring 22 is less than that of the lower disk 15, and somewhat greater than 35 that of the upper disk 17 when considering the diameter of the latter as that from the bottom or inner edge of one notch 19 across to the bottom or inner edge of an opposite notch 19.

40 Pivoted at 24 to the disk 16 is a lever 25, said lever extending over the ring 22 and having a slot 26 through which a pin or screw 27 extends from the ring 22. The lever has a handle 28 and a lug 29, and one of the arms 20 has a lug 30. The two lugs 29, 30, have holes 33 through which the hasp of a padlock may be passed. The margins of the recesses or notches 19 are preferably cushioned as indicated at 32 in Figure 1. Strips

of leather secured to the margins of said notches provide suitable cushions.

The marginal portions of the lower disk at the side ends of the notches 18 are upturned to form lugs 31 which serve a purpose 55 presently explained.

In use, if the rack is employed to hold rifles, shot guns, or articles other than guns, such articles may have their butts or lower ends resting on the floor, and they are leaned back into the recesses or notches of the upper and lower disks, and the handle 28 of the lever 25 is then operated to shift the ring 22 around far enough so that the hook members 23 extend across the outer sides of said articles. Such shifting of the ring 22 brings the two lugs 29, 30, close together, and a pad-lock 60 may be employed to lock the lugs in that position and effectively prevent either of the articles from being removed.

65 My improved rack however is especially intended for supporting machine guns of the Browning type, and for locking them in the rack when occasion renders such locking desirable. As is well-known, armories are not always so well guarded as to certainly prevent would-be thieves from gaining access thereto. The mounting of such guns in my improved rack, whereby unauthorized removal of one or more of them from the rack 70 is practically impossible, will now be explained.

75 Machine guns when in use are usually supported on tripods, but are separated from the tripods when not in use. Each Browning 80 machine gun has a certain aperture which is known as the "adapter mount", and has another part known as the "elevating bracket". Such guns when placed in my improved rack, 85 have their "elevating brackets" fitted to the recesses of the lower disk and portions of said brackets extend onto the projections at the ends of the recesses and behind the lugs 31, and the guns are leaned back into the recesses 90 of the upper disk, the series of guns then being in positions leaning toward a common center where they will readily remain without having any portion thereof resting on the floor. In other words, the lower disk sup- 95 100

ports the guns clear of the floor and all tending to remain in such positions without slipping out of the disk recesses. To aid in holding the guns accurately, the ring 22 is shifted to cause the hook members 23 to enter the "adapter mount" apertures of the guns, and then, if it is desired to reliably lock the guns in the rack it is only necessary to employ a pad-lock with its hasp in the holes 33 of the lugs 29, 30. The marginal recesses of the upper and lower disks provide sockets in which the guns rest, while the intermediate member consisting of the ring and its hooks provides means for so engaging the guns that are mounted in the sockets that unauthorized removal of any of the guns is practically impossible.

Having now described my invention, I claim:

1. A rack of the character described, having an upper series of stationary sockets and a corresponding lower series of stationary sockets, and an intermediate rotatable member having means thereon to engage articles mounted in said sockets when said member is rotated in one direction.

2. A rack of the character described, having an upper series of stationary sockets and a corresponding lower series of stationary sockets, and an intermediate rotatable member having means thereon to engage articles mounted in said sockets when said member is rotated in one direction, said rotatable member having means whereby it may be locked in article-engaging position.

3. In a rack of the character described, the combination with an upright having upper and lower disks fixed thereto, said disks having marginal recesses, of a laterally shiftable ring supported by said upright intermediate the upper and lower disks, said ring having laterally extending prongs positioned to shiftably engage articles resting in the recesses of the disks.

4. In a rack of the character described, the combination with an upright having upper and lower marginal recessed disks fixed thereto, of an intermediate disk also fixed to the upright and having a circular series of bearings, a ring mounted in said bearings and having laterally extending prongs, and means for locking said ring in position with its prongs engaging articles resting in the recesses of the disks.

5. In a rack of the character described, the combination with an upright having upper and lower marginally recessed disks fixed thereto, the lower disk being larger than the upper disk and having upright lugs at the ends of its recesses, of an intermediate circular series of hook-shaped members supported by the upright and rotatable relatively to the disks, means being provided for locking said series of hooked-shaped members in positions

in engagement with articles resting in the recesses of the disks.

In testimony whereof I have affixed my signature.

WILLIAM J. SPROWLE.
